Application February 16, 1953, Serial No. 23,643

Term of patent 14 years

(Cl. D48—20)

To all whom it may concern:

Be it known that we, Robert Goldman and Roy R. Nemzer, both citizens of the United States and residents of South Hempstead, in the county of Nassau, State of New York, have invented a new, original, and ornamental Design for a Music Box Nursery Lamp, of which the following is a specification, reference being had to the accompanying drawing, forming a part thereof, and of which

Fig. 1 is a front perspective view of a music box nursery lamp, showing our new design,

Fig. 2 is a rear perspective view thereof, and Fig. 3 is a side elevational view partly in per-

spective of the music box nursery lamp shown in Figs. 1 and 2 but with the monkey shown in an inverted position.

We claim:

The ornamental design for a music box nursery lamp, as shown.

ROBERT GOLDMAN.
ROY R. NEMZER.
